PAPER CUTTING MECHANISM

Thomas H. Hallwood, Columbus, Ohio, assignor
of one-half to William D. Belknap

Application May 9, 1932. Serial No. 610,101

7 Claims. (Cl. 242—55.5)

This invention relates to that class of devices intended to support rolls of wrapping paper and to mechanism for cutting the paper from the rolls in desired lengths.

5 An object of the present improvement is to provide a combination support and cutting mechanism whereby the latter may be adjusted relative to the support so that regardless of the position of the support, whether mounted upon the counter or wall surface, the cutting mechanism 10 may be arranged for proper working operation.

Another object of the invention is to provide 15 novel cutting means in the form of a bar with the paper so arranged relative thereto that it may be conveniently grasped at any point along its edge for the tearing thereof without the need of first turning the roll so as to advance the paper as is now the common practice with the 20 ordinary type of cutters.

It is also an object of the invention to provide 25 a mechanism of this kind which is extremely simple in its construction, reliable in its operation and one which is comparatively cheap or economical to manufacture.

With these and other objects in view, as will appear as the description proceeds, the invention consists in the novel features of construction, combination of elements and arrangement 30 of parts hereinafter to be fully described and pointed out in the subjoined claims.

In the accompanying drawings:

Fig. 1 is a perspective view showing a paper 35 roll mounted in connection with the improved paper roll support and cutting mechanism comprising the present invention;

Fig. 2 is a detail vertical sectional view taken through the paper cutting mechanism and the portion of the paper roll lying adjacent thereto;

40 Fig. 3 is a longitudinal sectional view taken through the cutting mechanism on the line 3—3 of Fig. 2;

Fig. 4 is a detail vertical sectional view taken through the fulcrum of the paper roll;

45 Fig. 5 is a horizontal sectional view taken on the line 5—5 of Fig. 4;

Fig. 6 is a transverse vertical sectional view taken on the line 6—6 of Fig. 7;

50 Fig. 7 is a vertical longitudinal sectional view taken on the line 7—7 of Fig. 6;

Fig. 8 is a view showing the paper roll support mounted on a vertical wall surface;

55 Fig. 9 is a similar view showing the support mounted on the under surface of a counter, ledge or the like.

Referring to the drawings in detail, numeral 1 designates the paper roll supporting structure in its entirety and comprising the upstanding end members or brackets 2 which are in this instance cast and each formed with a supporting foot 3 for attachment to a counter, wall or the like supporting surface. The lower ends of the brackets may be connected if desired by a bar 4 for the convenient spacing of the brackets during the erection thereof to a supporting base and for holding the same connected for shipping or handling purposes.

Carried by the upper or outer ends of the brackets 2 are adapter members 5 which in certain positions of the brackets 2 serve as extensions for the latter and in turn carry at their outer ends the cutting mechanism designated generally by the numeral 6. The adapter members 5 which have been designed particularly for the proper positioning of the cutting mechanism relative to the paper roll, are each formed with a disk like end 7 to conform in shape with the attaching ends of the brackets 2. Passing through the center of the disk 7 is a threaded fastening element or screw 8 which serves to rigidly unite the adapter member to the bracket support 2. It will be noted from reference to the drawings and particularly Figs. 6, 8 and 9, that the adapter members 5 are in each case arranged vertically whereas the brackets 2 may be positioned vertically, inverted or horizontally. This is an important feature in that it enables the paper roll support to be mounted either on top of the counter, its under surface or on a vertical wall without altering the construction or substituting parts of the support.

To hold the members 5 in correct position relative to the brackets 2, the disk like ends 7 are formed with lightly struck-up projections 9 which are received within similarly shaped depressions 10 formed in the brackets 2. The inter-locking relationship of the projections 9 and the depressions 10 also prevent axial rotation of the adapter members 5 with respect to the brackets 2 during the use of the supporting structure.

Provided upon the inner surfaces of the adapter members 5 and located at the inner ends thereof are bearing flanges 11 which are each provided with an arcuate socket 12 for the reception of the shaft 13 passing centrally through the paper roll 14. The sockets 12 are slightly spaced from the members 5 to provide spaces for the enlargements or heads 15 formed with the outer ends of the shaft 13. The heads 15 serve to prevent longitudinal sliding movement of the shaft and also form connections between the shaft and the sup-

porting brackets to brace the latter at their upper ends.

The cutting mechanism 6 which is carried by the outer ends of the adapter members 5 comprises a frame including a pair of side arms 16 which have one of their ends provided with fulcrum studs 17 received within bearing openings formed in the outer ends of the members 5. Connecting the other ends of the arms 16 is a 10 cutter bar 18 which in this case is formed of a strip of sheet metal having a suitable gauge to provide for the necessary rigidity and weight to the cutter frame. The bar 18 which extends the full length of the roll 14 has its ends provided 15 with down-turned flanges 19 which are attached to the inner surfaces of the arms 16 in any well-known manner as, for example, by spot welding the same thereto. Formed with the upper longitudinal edge of the bar 18 is a depending flange 20 20 which has its lower edge rounded and resting upon the paper roll. The opposite or lower edge 24 of the bar constitutes the cutter and may be turned downwardly or rounded slightly to protect the hand of the operator and to strengthen 25 the bar at this point. The rounding of the bar is however not essential from a cutting standpoint, as the edge may be straight and serve equally as well.

Arranged below the top wall of the bar 18 and 30 located near the upper edge thereof is a pair of rods 21 and 22 respectively over which the paper 23 is trained to take a somewhat tortuous path with the rod 22 acting to hold the free edge of the paper spaced from the cutting edge. This 35 spacing of the paper from the cutting edge provides for the convenient grasping of the paper and enables the operator to take hold of the paper at any point throughout the width thereof. If desired, the bar 21 may be made removable 40 to facilitate the insertion or training of the paper between the rods.

To effect this removal of the bar, a pivoted spring finger 25 is provided which is located exteriorly of one of the arms 16 and has its free end 45 formed with a slight depression entering one of the bearing openings formed in the arms for the rod. By swinging the finger 25 to one side, the rod may be pulled outwardly so as to free its ends from engagement with the bearings, as will be 50 readily understood.

In operation, it will be seen that as the operator grasps the free end of the paper and exerts an outward pull thereon, the paper will pass under the lower edge of the flange 20, over the rod 21 55 and under the rod 22 until the desired length of paper has been unwound at which time the paper is brought into engagement with the cutting edge and cut in the ordinary manner. After the cutting operation, the paper edge will drop down 60 to a position shown particularly in Fig. 2 which is due to the arrangement of the rod 22 and the tendency of the paper to straighten out. Due to the character of the paper which is somewhat stiff, the same will hold itself in engagement with the rod 22 and the free end thereof held in an 65 elevated position but yet spaced from the cutting edge of the bar. The flange 20 under which the paper is passed serves as a brake for the roll, and prevents the paper from sliding back and becoming 70 disengaged from its connection with the cutter bar.

From the foregoing it will be seen that a novel support for a roll of wrapping paper and a cutting mechanism for the paper thereof has been provided 75 which has several outstanding advantages in

that due to the construction thereof, the paper roll may be mounted on various supporting surfaces such as on top of a counter, the under side thereof or upon a vertical wall and yet maintain the cutting mechanism in its proper relation thereto. The cutting mechanism thereof also has the advantage of being efficient in its operation and will permit the ready grasping of the paper edge without the necessity of first turning the roll so as to advance the paper as has to be done with paper cutters of ordinary construction. Due to the particular arrangement of the paper relative to the cutter bar, the paper is spaced from said bar throughout the full length thereof so that the paper may be grasped at any point of its width thereby greatly facilitating the paper cutting operation.

What is claimed is:

1. A paper roll support comprising a pair of longitudinally spaced brackets adapted for attachment to a supporting surface, a pair of adapter members having one of their ends pivotally secured to the outer ends of said brackets, means formed with said adapter members for the rotative support of a paper roll therebetween, and a 100 paper cutting mechanism pivotally carried by the outer free ends of said adapter members.

2. A paper roll support comprising a pair of longitudinally spaced brackets adapted for attachment to a suitable supporting surface, a pair of bracket extensions having one of their ends pivotally secured to the outer ends of said brackets, bearings provided with the pivoted ends of said extensions for the rotative support of a paper roll, and a frame carrying a paper cutter pivotally mounted to the outer ends of said extensions.

3. A paper roll support and cutting mechanism comprising a pair of bracket members adapted for attachment to a supporting surface, extensions formed with said brackets which are pivotally secured to the outer ends of the latter and capable of being positioned angularly with respect thereto, bearings formed with said extensions for the rotatable support of a paper roll therebetween, and a cutter carrying frame pivotally connected 115 to the outer ends of said extensions.

4. In combination with a support for a paper roll, of a paper cutter mechanism for the paper of said roll comprising a frame extending longitudinally of said roll and having its ends pivoted 125 to said support, said frame including a longitudinally extending bar having an edge thereof engaging said roll, the other edge which constitutes the cutter being spaced from said roll, and a pair of longitudinally extending members carried in 130 connection with said bar and located near the inner edge thereof, said members having the paper from the roll trained therebetween and serving to hold the edge of the paper in a spaced relation from said cutting edge.

5. In combination with a support for a paper roll, a frame pivoted to said support and extending longitudinally of said roll, said frame including a longitudinally extending bar having an edge resting upon said roll and serving as a brake 140 therefor, a cutting edge formed with the other longitudinal edge of said bar, a pair of longitudinally extending rods carried by said frame and located in a plane above the roll engaging edge of the bar, whereby due to the location of these 145 rods, the paper will pass under the inner edge of said bar and between said rods in such manner as to keep the free edge of the paper spaced from said cutting edge.

6. A paper cutting mechanism adapted for at-

tachment to a paper roll supporting structure, said mechanism including a frame pivoted to said supporting structure, said frame including a bar having one of its longitudinal edges formed 5 with a down turned flange resting upon said roll and serving as a brake therefor, a cutting edge formed with the opposite longitudinal edge of said bar, and a pair of longitudinally extending rods located adjacent the inner edge of said 10 bar and positioned in a plane above the latter, said rods together with the inner edge of said bar serving to hold the free edge spaced from said cutting edge.

7. A paper roll and cutting mechanism support comprising a pair of longitudinally spaced bracket members adapted for attachment to a suitable supporting surface, a pair of adapters arranged between said bracket members and having one of their ends pivotally secured to the outer ends of said bracket members, sockets provided with the pivoted ends of said adapters for the rotative support of a paper roll, said sockets being open towards the outer free ends of said adapters, and a paper cutter frame pivotally connected to the outer ends of said adapters. 85
